UNITED STATES PATENT OFFICE.

LOUIS MATHIAS OROSZ, OF ERZSÉBETFALVA, AUSTRIA-HUNGARY, ASSIGNOR
OF ONE-HALF TO MORITZ HAY, OF BUDA-PESTH, AUSTRIA-HUNGARY.

COUPLING FOR RAILWAY-CARS.

SPECIFICATION forming part of Letters Patent No. 630,817, dated August 8, 1899.

Application filed July 5, 1898. Serial No. 685,148. (No model.)

To all whom it may concern:

Be it known that I, LOUIS MATHIAS OROSZ, a subject of the Emperor of Austria-Hungary, residing at Erzsébetfalva, near Buda-Pesth, in the Empire of Austria-Hungary, have invented certain new and useful Improvements in Couplings for Railway-Cars, (for which I have applied for patents in England, dated May 5, 1898, No. 10,322; in France, dated May 5, 1898, No. 265,446; in Belgium, dated May 5, 1898, No. 105,712; in Austria, dated May 4, 1898; in Hungary, dated April 27, 1898, No. 6,002, and in Germany, dated March 22, 1898,) of which the following is a specification.

15 Side-operated couplings for railway-cars have hitherto not come into universal use, partly because they have been too complicated and partly because the important fact has been overlooked that the car-couplings 20 are different heights when loaded and when empty.

The object of the present invention is therefore to provide a coupling for railway-cars operated from either side which is characterized by great simplicity and adapts itself automatically to the various load-levels of the cars.

In the accompanying drawings, which illustrate the invention, Figure 1 is a detail longitudinal sectional view of parts of two cars, showing my improved coupling in sectional elevation. Fig. 2 is a top plan view of one-half of Fig. 1, and Fig. 3 shows in two detail views the operating-lever and locking device.

Beneath the car-frame *a* is journaled an operating-shaft *b*, having its ends which project beyond the car-body bent at right angles to form lever-arms or cranks *b'*. At the 40 middle of the length of the shaft *b* is rigidly mounted a rock-arm *c*, which arm, through an intermediate link *d*, is connected to the double arm or link *g*, working on the pivot *g'* of the link-frame *f* and carrying the double hook *h* *i*. With the help of the cranks *b'* the shaft *b* may be rotated from either side of the car, carrying with it the fixed arm *c*, and through the intermediate link *d* swinging out the coupling-link *g*, carrying the double hook *h* *i*. The hooks *h* and *i* each terminate in a

slanting back portion *h'* or *i'*, giving the hooks a heart shape, ending in a point *K*.

If two cars provided with the same device are to be coupled together, the shaft *b* is brought into position by means of the crank *b'*, so that the arm *c* is horizontal, and the shaft is locked in this position by means of the hook *b*² engaging with the crank portion *b'*. (See Fig. 3.) The two are then moved toward each other, and accordingly as they are loaded or empty their bodies will occupy a higher or a lower level and the upper or lower surfaces *h'* or *i'* of the double hook of one car-coupling will engage with the bolt *l* of the double coupling-link *g* of the other coupling. The particular surface *h'* or *i'* which engages with the bolt *l* determines which of the two hooks, whether *h* or *i*, shall come into operation; but in either case the coupling of differently-weighted vehicles holding their couplings at different levels is provided for. To support the link *g*, carrying the double hook, in position upon frame *f*, the rear end or heel *g'* of said link engages a pin *f'* in the link-frame *f*. For drawing the coupling together a shaft *m* is provided, which may be rotated with the aid of the lever or crank *m* upon each car to drive the worm-wheels *n* *n'*. Fast with the worm-wheel *n'* is connected a screwed sleeve *p*, placed on the opposite side of the fixed plate *r*. On this sleeve *p* works the screwed spindle *o'*, which spindle terminates in the draw-bar *o*, carrying the link-frame *f*, pivoted on the pin *e*. For further supporting the coupling the link *g* is connected to the draw-bar *o* on both sides by the pivoted rods *x* and *y*, so that in case the pin *g'* or the link-frame *f* breaks the pivoted rods *x* *y* will be drawn out and the coupling remain secure. Before the parts of the coupling engage the coupling-hooks *h* and *i* may be so positioned by means of the crank *m* that a secure grip of the parts of the coupling is insured, and this is rendered possible by the fact that the arm *c* on the shaft *b* is connected to the link *g*, which carries the double hooks *h* and *i*, through the intermediate link *d*. When the couplings are approximately brought to position by lengthening or shortening the draw-bar *o*, the cars are pushed together in the usual 100

manner, and then one or other of the hooks *h* or *i* will engage by the sloping portion *h'* or *i'* riding over or under the bolt *l*. It will thus be seen that only one-half of the coupling, 5 either *h* or *i*, engages the bolt *l*, so that in the case of a hook or a bolt breaking the other hook or bolt will still be available for holding the coupling, and a double security is thus attained. When the parts are engaged, 10 the worm-wheels *n* and *n'* are rotated by one of the cranks *m*, thus providing a method of drawing the couplings together. The couplings are released in the same simple way, it being only necessary to rotate one of the 15 cranks *m* in the reverse direction and after pushing aside the catch *b*² to take hold of the cranks *b'* and lift the coupler-hooks.

Having thus described my invention, what I claim as new, and desire to secure by Letters 20 Patent, is—

1. In a car-coupling, the combination of a draw-bar, a coupling-supporting frame mounted upon the draw-bar, a double-hook

coupling-link supported upon said supporting-frame, links *x* and *y* connecting the coupling-link with the draw-bar and manually-operated controlling devices upon the car connected with the coupling-link, substantially as set forth. 25

2. In a car-coupling, the combination of 30 a draw-bar, a coupling-supporting frame pivotally mounted upon the draw-bar, a double-hook coupling-link pivoted upon the supporting-frame, a heel *g'* upon the coupling-link, a pin *f'* upon the supporting-frame engaged by 35 the heel *g'* for supporting the coupling-link upon said frame, and manually-operated controlling devices upon the car connected with said pivotally-mounted supporting-frame, substantially as set forth. 40

In testimony whereof I have hereunto set my hand in the presence of two witnesses.

LOUIS MATHIAS OROSZ.
